UNITED STATES PATENT OFFICE.

BENJAMIN P. ALLEN, OF GREAT NECK STATION, NEW YORK.

EXPLOSIVE.

1,284,032.

Specification of Letters Patent.

Patented Nov. 5, 1918.

Application filed June 9, 1917. Serial No. 173,812.

To all whom it may concern:

Be it known that I, BENJAMIN P. ALLEN, a citizen of the United States, residing at Great Neck Station, in the county of Nassau 5 and State of New York, have invented certain new and useful Improvements in Explosives, of which the following is a specification.

This invention has relation to ammunition 10 for military purposes, and has for an object to provide a projectile adapted to be projected from any suitable weapon, or to be released from an air ship, and embodying means for containing a plurality of 15 darts and for projecting the same from the projectile, with a view to increasing the efficiency of the projectile.

A still further object of the invention is 20 to provide a projectile embodying means for containing and projecting a plurality of darts, and embodying an explosion chamber controllable by a percussion fuse whereby the shell may be exploded when striking any object offering resistance, subsequent 25 to the releasing of its charge of darts.

A still further object of the invention is to 30 provide a projectile having the above named characteristics and embodying a plurality of chambers defined by walls which are provided with channels, said chambers being 35 filled with explosives and normally out of communication with each other and each filled with materials which form an explosive when mixed, whereby the walls may be shattered by the explosion of the shell and the ingredients permitted to mix to exert a great dynamic force at the time that the shell reaches its destination.

In addition to the foregoing my invention 40 comprehends improvements in the details of construction and arrangement of the parts to be hereinafter more fully described and particularly set forth in the appended claims.

45 In the accompanying drawings in which similar and corresponding parts are designated by the same characters of reference throughout the several views in which they appear:

50 Figure 1, is a longitudinal sectional view of a projectile embodying my improvement, and

Fig. 2, is a view in section of one of the darts.

55 My invention is in the nature of a projec-

tile designed especially to be projected from a weapon and to that end it is uniform in diameter throughout its length, and conforms in appearance to the conventional type of shell having one end blunt and the other end sharpened. This shell comprises a section 30 open at both ends with one end 60 interiorly threaded to receive a removable cap 31 forming a closure and constituting the rear end of the projectile, the other end 65 being threaded externally to receive the internally threaded flange 32 of the head 33 which is closed at the flanged end by means of the partition 34. The section 30 is formed at a point intermediate its end with a transverse partition 35 defining compartments 36 and 37, said compartment 37 being furthermore divided by means of an annular partition 38 into a compartment 39 and a compartment 40. The partition 38 is drilled 70 with openings 41 which extend longitudinally through the partition to a point adjacent the forward end thereof and at the rear end communicate with the compartment 36 as indicated. A percussion fuse 42 may be 75 provided in the partition 35 for communication with the compartment 36, although said fuse may be located in the side wall of the section 30 if desired.

The pointed terminal of the head 33 of 80 the shell is provided with a plurality of longitudinally extending openings 43 in which to receive darts 44 which may be solid throughout as shown in Fig. 2. The terminal of the head is provided with a time fuse 85 45 of conventional type and the interior of the head is filled with a slow burning charge of explosive through a filling opening closed by a plug 46. The compartment 36 is filled with a charge of high explosives. 90

In use, the compartments 39 and 40 midway the length of the shell are filled with fluid kept out of contact by means of the walls or partitions 38 which fluids are of such a nature as to explode spontaneously 100 when mixed. Prior to the discharge of a projectile of this type from the weapon, the time fuse 45 is set so as to explode the charge within the head of the projectile at a time when the shell has very nearly completed its trajectory, and arrives at a point somewhat above the surface of the earth whereupon the charge within the head will create pressure sufficient to forcibly eject the darts therefrom with an initial velocity 105 110

- greater than the velocity of the projectile at the time of the explosion of the charge. When the shell engages an object having sufficient resistance to insure operation of the percussion fuse 42, the charge within the compartment 36 will be exploded and the flame communicated to that portion of the charge located within the drilled openings 41 of the partition 38 whereupon the said partition will be shattered and the contents of the compartments 39 and 40 permitted to mix so as to cause an explosion whereby the entire shell will be shattered and its fragments carried in all directions.
- 15 While I have illustrated and described my invention with some degree of particularity, I realize that in practice that various alterations thereover may be made, and I therefore reserve the right and privilege of changing the form of the details of construction, or otherwise altering the arrangement of the correlative parts without departing from the spirit of the invention or the scope of the appended claims.
- 20 25 Having thus described my invention what I claim as new and desire to secure by Letters Patent is:
1. A projectile having a high explosive containing compartment, and a second compartment, a partition in said second compartment defining a plurality of sub-compartments designed to contain materials in

separated relation which materials form an explosive when mixed, said partition defining said sub-compartment having passages extending therethrough in communication with the first compartment only, and a fuse for exploding the charge of the first compartment whereby the walls of the said compartments may be shattered to permit the said materials to mix whereby to shatter the entire projectile.

2. In a projectile having a transverse partition defining two compartments, an annular partition in one compartment defining a pair of sub-compartments, said annular compartment having longitudinal channels formed therein communicating at one end with the other compartment, and dissimilar liquids in the sub-compartments, adapted when mixed to form an explosive mixture.

3. A projectile having its wall perforated and its interior filled with explosives, and a plurality of darts including cylindrical shanks inserted in the openings and having conical outer terminals for penetrating the object.

In testimony whereof I affix my signature in presence of two witnesses.

BENJAMIN P. ALLEN.
